C. C. Shepherd Attorney

UNITED STATES PATENT OFFICE.

GEORGE W. GOSS, OF BALTIMORE, OHIO, ASSIGNOR OF ONE-HALF TO CHARLES E. GOSS, OF BALTIMORE, OHIO.

GATE-LATCH.

1,358,077.

Specification of Letters Patent.

Patented Nov. 9, 1920.

Application filed July 10, 1919. Serial No. 309,845.

To all whom it may concern:

Be it known that I, GEORGE W. Goss, a citizen of the United States, residing at Baltimore, in the county of Fairfield and State of Ohio, have invented certain new and useful Improvements in Gate-Latches, of which the following is a specification.

This invention relates broadly to farm gates of the horizontal swinging variety, and has particular reference to an improved latch structure adapted for use in securely locking a gate equipped with the same against undue swinging movement.

The primary object of the invention resides in the provision of a latch structure wherein is embodied an attaching member which is mounted for longitudinal sliding movement upon one of the gate bars, and from which projects a longitudinally disposed locking tongue which is adapted to project into a locking recess formed in a co-operative post member, said locking tongue being provided with a curved portion in its length forming a handle which upon being grasped will enable said tongue and its associated member to be reciprocated upon the gate bar so that the locking extremity of said tongue may be either projected into or out of engagement with said post recess.

Another object of the invention resides in equipping the attaching member with an improved friction creating element which is so disposed as to engage with one or more sides of the gate bar upon which the member is carried said element serving to frictionally engage said bar so that said tongue and member will be retained in their severally adjusted positions.

Other objects of the invention will be in part obvious and in part pointed out hereinafter.

For a further understanding of the invention, reference is to be had to the accompanying drawing, forming a part of the present specification, and in which:

Figure 1 is a side elevation of a farm gate equipped with a latch structure comprising the present invention.

Fig. 2 is a perspective view of the latch structure showing the same detached from the gate.

Fig. 3 is a top plan view of the hinge struc-

ture of the gate upon which the latch structure is mounted, and,

Fig. 4 is a detailed top plan view.

Referring more particularly to the details of the invention, use is made of a gate structure 1. This structure may be of any desired formation but inasmuch as the form disclosed clearly sets forth the principles of the present invention, the following description will be accordingly confined thereto. In this instance the gate structure consists of a plurality of spaced longitudinally extending wooden bars 2, which are joined and held in their operative positions by means of vertically extending angle irons 3, the latter being preferably disposed in pairs which are mounted on opposite sides of the bars 2, as is clearly shown in Fig. 4. To effect the hinging of the gate, so that the latter may swing in a horizontal direction, use is made of pairs of metallic plates 4, which are mounted upon the upper and lower bars of the gate structure at the hinge end of the latter, and said plates are suitably secured as at 5 to their respective bars. Diagonal brace members 6 are also carried by the gate and serve to strengthen the hinge end of the latter, said braces terminating contiguous to the ends of the plates 4, and passing through the ends of said plates and said diagonal braces are bolts 7 which carry reversible hinge elements 8. A post member 9 is employed to support the gate structure and is provided with pintle members 10, the latter having their vertically disposed portions situated to extend through the elements 8 so as to lie between the latter and the securing bolts 7. In this manner said bolts may rest upon the horizontal portions of the pintles and the gate maintained in a supported condition. By reversing the positions of the hinge elements 8, the free end of the gate may be raised or lowered so that a free swinging position of the gate may be maintained.

Coming now to the more essential features of the invention, the latch structure is indicated by the letter A, this structure being employed to lock the gate against swinging movement at desired intervals.

In its preferred form the structure A consists of a strip of channel iron which is bent to assume an inverted U shaped for-

mation and provides a yoke or attaching member 11. The vertical legs 12 of the member 11 are adapted to receive between the same one of the bars 2 of the gate structure so that said yoke member may be supported for longitudinal sliding movement upon said bar. A latch tongue 13 also formed from channel iron extends laterally from the yoke member and has its inner 5 end secured by means of a rivet 14 to the upper portion of the yoke member. Said tongue is adapted to rest upon the upper edge of the bar upon which the yoke member is slidably mounted, and the forward end 10 of said tongue terminates in a reduced locking extremity 15. This extremity is adapted to be slidably projected into or out of engagement with any one of a plurality of vertically disposed locking recesses 16, provided in a coöperative post member 17, and 15 said tongue is provided in its length with a curvilinear portion 18 which provides a handle for enabling the tongue to be manually grasped, so that its reciprocation may 20 be conveniently effected. The forward portion of the locking tongue is adapted to pass between the end angle members 3, and in this manner, the movements of said tongue will be effectively guided, one end thereof 25 being carried by the yoke member 11 while the opposite end operates between said angle members. By providing a plurality of alined recesses 16 in the post member 17, said tongue will be enabled to register 30 with at least one of said recesses irrespective of the adjustments in the gate to overcome sagging.

In order to maintain the tongue in its severally adjusted positions, said yoke member is provided in this instance with a relatively strong leaf spring 19 which has one of its ends bent so as to be interposed between the inner end of the tongue and the upper portion of the yoke member, 40 the rivet 14 being employed to retain said spring in its operative position. When the yoke member is positioned upon one of the bars 2, said spring will be frictionally forced against one side of the bar upon which 45 the member is mounted and will exercise sufficient pressure thereon to retain the yoke member substantially immovable against accidental displacements. The pressure exercised by the spring 19 may be regulated 50 through the provision of a bolt 20. The latter is arranged to pass through the lower free ends of the legs 12 and is suitably threaded for the reception of a nut 21. Obviously, by 55 tightening the nut 21 against the legs 12, the latter will be contracted to such extent that the spring 19 will be forced into firm frictional contact with a coöperative bar. Thus, 60 if the spring should weaken after extended use, such weakness may be largely overcome 65 by adjusting the nut 21.

From the foregoing description, taken in connection with the accompanying sheet of drawing, it will be apparent that there is provided a latch structure of considerable utility and one which may be conveniently 70 operated to assume its various operative positions. It will be noted that the structure as a whole is supported on the bar upon which the yoke member is mounted and that through the provision of the spring 19, said 75 tongue will be maintained against accidental displacement. Also, by projecting the forward end of the tongue between the angle irons 3, the alinement of the locking end of said tongue with respect to the recesses 16 80 will be insured, thus producing a structure of a very reliable and positive nature.

What is claimed is:

1. In a farm gate, a latch structure therefor comprising a slidably mounted member 85 arranged upon one of the longitudinal bars of a gate structure, a latch tongue extending laterally from said member and disposed to lie parallel with the edge of said bar upon which said member is mounted, a post having 90 a locking recess formed therewith and into which the end of said tongue is capable of slidably projecting, and means carried by said member for retaining said tongue in its 95 adjusted positions.

2. In a farm gate, a latch structure therefor comprising a slidably mounted member carried by said gate, a latch tongue extending from said member and capable of being reciprocated in unison therewith, the end of 100 said tongue being adapted to engage with a recess formed in the post member in order to lock said gate to said post member, and friction imparting means carried by said first named member for retaining said tongue in 105 its severally adjusted positions.

3. In a farm gate, the combination with the longitudinally extending bars thereof and the vertically disposed and connecting angle members therefor, of a latch structure 110 for said gate comprising a member slidably received through longitudinal adjustment upon at least one of said bars, a locking tongue carried by said member and arranged to pass between certain of said angle members for guided movement and to enter a recess formed in the adjoining post member, and means for frictionally retaining said member and tongue in their slidably adjusted 115 positions upon said bar.

4. In a farm gate, a latch structure therefor comprising a slidably mounted member arranged to be carried by one of the longitudinal bars of said gate, a tongue connected with said member and mounted to extend 120 parallel with said bar, one end of said tongue being provided with a locking extremity 125 designed for engagement with a coöperative post member to retain said gate in locked relation therewith, means for guiding the 130

locking extremity of said tongue, and spring means carried by said slidably mounted member and arranged to bear upon said bar so as to retain said tongue in its slidably adjusted 5 positions.

5. In a farm gate, a latch structure therefore comprising a slidably mounted U shaped member, the latter being arranged to be slidably positioned upon one of the longitudinal 10 bars of said gate, a locking tongue connected with said member and extending longitudinally upon the upper edge of the bar upon which said member is carried, said tongue being provided with a locking extremity designed 15 for engagement with one of a plurality of recesses formed in a post member, angle irons connecting the longitudinal bars of said gate and between which said tongue

is projected and guided, spring means carried by said member and disposed to frictionally engage with the bar upon which 20 said member is carried to retain said tongue in its adjusted positions, and threaded means carried by the free ends of said U shaped member and arranged to govern the frictional relation between said spring and said 25 bar.

6. The structure as specified in claim 5 and wherein said tongue is provided with a longitudinally curved portion forming a manipulating handle. 30

In testimony whereof I affix my signature.

GEORGE W. GOSS.
